DESIGN FOR A BROOCH

James McIntosh Grigor, Inverness, Scotland

Application March 29, 1937, Serial No. 68,465
In Great Britain February 10, 1937

Term of patent 14 years

To all whom it may concern:

Be it known that I, James McIntosh Grigor, a subject of the King of Great Britain, residing at 16-20 Hamilton Street, Inverness, Scotland, have invented a new, original, and ornamental Design for a Brooch, of which the following is a specification, reference being had to the accompanying drawing, forming part thereof.

Fig. 1 is a front elevation, Fig. 2 a rear ele-

vation, and Fig. 3 a perspective view from the rear, showing the brooch in normal condition. Fig. 4 is a view corresponding to Fig. 2 but with the safety-pin of the brooch turned about its pivot through 180° from the position shown in Fig. 2.

I claim:

The ornamental design for a brooch, as shown.

JAMES McINTOSH GRIGOR.
